DESIGN FOR A COMBINED DISPLAY STAND AND CONTAINER

Benno Zimmern, New York, N. Y.

Application June 6, 1946, Serial No. 130,467

Term of patent 3½ years

(Cl. D80—9)

To all whom it may concern:

Be it known that I, Benno Zimmern, a citizen of the United States and a resident of the city of New York, in the county and State of New York, have invented a new, original, and ornamental Design for a Combined Display Stand and Container, of which the following is a specification, reference being had to the accompanying drawing, constituting a part thereof in which:

Fig. 1 is a top plan view of my combined display stand and container;

Fig. 2 is a front elevational view; and

Fig. 3 is a perspective view with the container shown separated from the display stand.

I claim:

The ornamental design for a combined display stand and container, substantially as shown.

BENNO ZIMMERN.
